United States Patent Office

Des. 205,322
Patented July 19, 1966

205,322

PHOTOGRAPHIC PRINTER

Ralph M. Vigna, Rochester, N.Y., assignor to Eastman
Kodak Company, Rochester, N.Y., a corporation of
New Jersey

Filed June 8, 1965, Ser. No. 85,616

Term of patent 14 years

(Cl. D61—1)

FIG. 1 is a front perspective view of a photographic printer showing my novel design;

FIG. 2 is a front view thereof;

FIG. 3 is a rear view thereof;

FIG. 5 is a rear view thereof;
FIG. 4 is a top plan view thereof;

FIG. 4 is a top plan view thereof; and

FIG. 5 is a left-end elevational view thereof, and

The broken line showing of a film or paper strip in FIGS. 1, 2, and 3 is for illustrative purposes only.

I claim:

The ornamental design for a photographic printer, as shown and described.
